UNITED STATES PATENT OFFICE

JOSEPH W. BECK, OF SPOKANE, WASHINGTON

RANGE

Application filed September 2, 1930. Serial No. 479,269.

My invention relates to ranges and more particularly to kitchen ranges or cook stoves. Certain objects of the invention are to provide a range having two ovens with a fire compartment interposed therebetween and a main down draft flue for said compartment together with a draft conduit extending around both of said ovens to the smokestack whereby the ovens are heated evenly and efficiently. A further object is to provide an auxiliary draft arrangement for use when the main vertical draft is shut off. Other objects are to provide a novel arrangement of grate bars, water coils and associated elements within the fire compartment. Still further objects are to provide other novel details of construction and arrangement as hereinafter set forth and described.

With the above and other objects in view which will appear as the description proceeds, the invention consists of the novel construction, adaptation, combination and arrangement of parts hereinafter described and claimed. These objects are accomplished by devices illustrated in the accompanying drawings, wherein:

Figure 1 is a general exterior view in perspective of the range;

Fig. 2 is a view in longitudinal vertical section of the same;

Fig. 3 is a detail view in perspective of the grate;

Fig. 4 is a view in vertical section of the grate taken on a broken line 4,4 of Fig. 3;

Fig. 5 is a fragmentary view of the range partly in top plan and partly in horizontal section;

Fig. 6 is a view in transverse vertical section of the range taken substantially on a broken line 6,6 of Fig. 2;

Fig. 7 is a fragmentary view in vertical section taken on a broken line 7,7 of Fig. 5;

Fig. 8 is a detail view in section taken on a broken line 8,8 of Fig. 2 and showing the means for protecting the glass windows;

Fig. 9 is a fragmentary view in vertical section taken on a broken line 9,9 of Fig. 5 and showing the smokestack damper and soot collecting pit; and

Fig. 10 is a view in perspective of the auxiliary draft and its controlling means.

Referring to the drawings throughout which like reference numerals indicate like parts, the numeral 5 designates the outer casing of the range as a whole. A main baking oven 6 occupies substantially one-half side portion of said casing and a smaller slow baking oven 7 is disposed within its other half side portion. Said ovens are spaced apart to provide a central fire compartment 8. The tops, ends and bottoms of said ovens are spaced away from the outer range casing walls thus providing a draft conduit 9 extending from the fire compartment around the ovens. Said conduit is slightly raised at 10 immediately below the fire compartment so that the hot draft therethrough will be quickened in its passage around the slow baking oven, and a baffle 11 projecting from the connecting point of the smokestack 12 provides means whereby the hot draft will be spread over the top of said oven before passing out through said stack. It will be noted that all corners of the conduit are rounded so that hot gases will pass through more freely. A soot pit 13 disposed immediately below said stack and also below the draft conduit is adapted to catch the soot falling from the stack and prevent it from obstructing the draft. The usual pivoted damper 14 is provided at this point as will be understood.

An ash pan 15 is disposed in the bottom of the fire compartment 8 and a fire box 16 is detachably mounted in its top portion. Water coils 17 are arranged on both sides of said compartment and the bottom of said fire box impinges said coils as shown in Fig. 7. The grate 18, as shown in detail in Fig. 3, comprises a plurality of spaced concave bars rigidly secured to a shaker shaft 19 at points offset from their centers. Said shaft is pivotally mounted through the range casing 5 and the heavier or remoter ends of the grate bars rest on a tubular member 20. Thus the grate may be shaken by slight pivotal movement or its may be completely turned over to dump the ashes as shown in dotted lines in Fig. 2 of the drawings.

The tubular member 20 is open at both ends

which project through both the front and rear walls of the casing 5. Said open ends are each adapted to be closed by discs 21 that are mounted fixedly on the exterior ends of a rod 22 passing pivotally through said range casing immediately below said tubular member and whereby both of said ends may be opened or closed at the same time by turning said rod. The major central portion of said tubular member is cut away, as at 23, thus providing auxiliary draft means for the fire when the discs are opened. When said discs are closed they may recede into flanges or lips 24, shown in Fig. 7, thus causing an air tight closure.

15 The main draft enters the fire compartment 8 below the grate 18 through a vertically disposed pipe 25 that extends upwardly alongside the smokestack 12 to a point near the ceiling of the kitchen. Thus said draft will draw off the smoke, fumes and noxious gases from the top of the room which are warm and will therefore cause better combustion. Said draft is controlled by a slideable damper 26 and should the fire become too hot or should too much warm air be taken from the room by the main draft said slideable damper may be closed and the auxiliary draft may be used by opening the ends of the tubular draft member 20.

20 The top 27 of the range has a large movable plate 28 above the oven 6, a smaller movable plate 29 above the oven 7, and a central movable plate 30 above the fire compartment 8 having the usual disc lids. A fueling door 31 may be either pivoted to said central plate to swing upwardly or pivoted to the front of the range casing 5 to swing outwardly thus providing ready access to the fire compartment. A double plate 32 is slidably disposed immediately below said fueling door in the front of the range and when said plate is removed the grate 18 may be lifted out.

25 The cleanouts 33 under the ovens 6 and 7 respectively are the full lengths of said ovens whereby soot may be readily removed therefrom. The bottom of the oven 7 being raised above the bottom of the oven 6 provides means whereby a drawer 34 may be installed for storage of utensils or use as a warming oven. The warming oven 35 is provided with slideable doors 36 and is excessively large thus providing ample room whereby said doors may be closed when dishes or pans of food are placed therein and thus providing means whereby the food may be kept warm.

30 The doors 37 and 38 for the ovens 6 and 7 respectively may be provided with the usual thermometers and also with windows 39 through which the cooking foods may be observed. Shutters 40 may be pivotally arranged to swing over said windows when they are not in use to protect them from breakage. Similar windows may be provided in the rear of the range for the admission of light into the ovens if so desired.

It will now be apparent that I have provided a range having two ovens and draft means whereby the ovens are evenly and efficiently heated together with auxiliary draft, damper, grate and other means whereby the utility and efficiency of the range as a whole is materially improved.

Having thus described my invention, it being understood that minor changes in its construction and arrangement may be resorted to without departing from the scope and spirit of the invention, what I claim and desire to secure by Letters Patent of the United States is:—

1. A range comprising a pair of spaced apart ovens, a fire compartment between said ovens, a main vertical draft, a draft conduit extending from said fire compartment around both of the ovens, a fire box for the upper end of the compartment, a grate eccentrically pivoted at the bottom of the fire box, a horizontal auxiliary draft tube for the fire compartment, and the heavier portion of the grate normally resting on said draft tube.

2. A range comprising a pair of spaced apart ovens, a fire compartment between said ovens, a pivoted door for said compartment, a main vertical draft, a draft conduit extending from said fire compartment around both of the ovens, said conduit slanted upwardly under one of the ovens, a smokestack at the discharge end of the conduit, a soot pit at the bottom of said smokestack, a fire box for the upper end of the fire compartment, water coils impinging the bottom of the fire box, a grate eccentrically pivoted at the bottom of the fire box, a horizontal auxiliary draft tube for the fire compartment, and the heavier pivoted end portion of the grate normally resting on said draft tube.

In testimony whereof I affix my signature.

JOSEPH W. BECK.
